Mass.

Application November 12, 1936, Serial No. 110,492

1 Claim. (Cl. 51—278)

The present invention relates to a method and apparatus for treating foil, such as aluminum or other metal foils, and also for the treatment of thin sheets of any type of material that is wound in rolls or comes in long strips. More particularly the invention relates to apparatus for mechanically roughing smooth metal foil such as aluminum, copper, tin or foils of other metals, and in particular for the preparation of aluminum foils in the manufacture of electrolytic condensers.

Up to the present time the common practice has been to treat by certain chemical processes aluminum foils of a similar nature that are used in the manufacture of electrolytic condensers to provide a more porous surface in order to enlarge the area upon which the electrolytic film might form. In this treatment the foil is passed through a so-called etching bath which chemically attacks the foil and eats away the surface in spots making it rough and porous in order to provide a large surface area upon which the electrolytic film forms. The chief difficulty with the chemical process is that the foil is not always uniform and oftentimes more of the surface is etched away than is really desirable. Due to the character of the foil itself some parts of it that may originally have a more highly polished surface than the rest or that may be of slightly different characteristics than the rest, may not be chemically acted upon to the same extent that other parts of the foil is, with the result that unless the process is carefully observed, the foil may not be uniformly treated.

In addition to this the chemicals and acids may oftentimes combine with certain impurities in the foil itself, or actually form with the foil certain compounds that may be injurious to the article when actually completed.

By means of the present invention aluminum foil is mechanically treated in such a manner that no chemical action is necessary, and as a result therefore, the foil after treatment is completed still remains pure aluminum foil prepared to receive its proper process in the manufacture of electrolytic condensers. It has also been found that with the present method and apparatus, the foil is treated very uniformly and slight irregularities do not prevent a uniform result from being obtained in the treatment. While the present foil after treatment may be called a mechanically etched foil, nevertheless, it more properly is a mechanically prepared foil to provide an increased surface area and to make it more ready to receive the chemical treatment in the preparation of electrolytic condensers.

In the present invention the novelty not only resides in the foil itself, but in the method and apparatus used in its preparation. The foil treated in the present invention usually comes in

rolls which may be any desired width as for instance $\frac{3}{4}$ inch, one inch, or even wider dimensions. The character of such foil is usually such that the general methods frequently applied for roughing surfaces cannot be employed. This is chiefly due to the fact that the foil is very weak in itself and will easily tear and also because the area of the surface that must be treated is so tremendous that any mechanical means must necessarily move rapidly over its surface.

In the present invention the method and apparatus is such that both of these difficulties have been overcome, and it is possible to treat metal foil of quite flimsy character in such a uniform manner that electrolytic condensers made from it will be uniform and possess the definite predetermined characteristics that are desired. The method will be more fully described in connection with the apparatus and also forming a part of the present invention. In the parts used in the present invention the metal foil is treated in a continuous process, the metal being unwound at one end of the machine and wound up again in a complete roll at the other end of the machine in such a manner that the foil is ready for processing in the manufacture of electrolytic condensers or for other purposes for which the foil may be used.

The present invention will be more fully described in connection with the drawings showing an embodiment of the same, in which—

Figure 1 shows a perspective of the front end of the machine where the treatment commences. Figure 2 shows a rear part of the machine where the washing and rewinding occurs.

Figure 3 shows a detail of the means used for guiding the foil.

Figure 4 shows an enlarged view of one end of the grinding rolls.

Figure 5 shows a sectional view of a chuck member in which the grinding roll fits.

Figure 6 shows a section on the line B—B' of Figure 5.

Figure 7 shows an end view of the spindle mechanism for winding the roll, and

Figure 8 shows a section on the line A—A' of Figure 7.

In Figure 1, the roll not shown provides a strip 1 which fits to the machine beneath the lower roll 2 and the upper roll 3 passing over the upper roll as indicated by the strip 1 on this roll. The strip then passes downward into a tank 4 which is filled with an abrasive compound 5 which will be described later. Inside of the tank 4 is positioned a roller 6 fitted into the sides 55 of the tank so as to allow it to roll freely. The strip 1 is passed beneath the roller 6 as indicated by the dotted lines and comes upward in the back of the tank. The tank 4 may be supported in the frame 7 by means of ears 8 extending 60

- from either side of the tank through which the rod 9 may pass, which itself is supported in the frame 7, the frame 7 comprising the two angle elements as indicated with suitable cross supports.
- 5 The strip 1 coming upward from the tank, passes between two wiping rollers 10 and 11 which may be mounted in an extension from the wall of the tank itself. From these wiping rollers the strip 1 passes between a series of pairs of abrasive rollers 12, 13, 14 and 15 which work in pairs as will be described later. After passing through these rollers, the strip 1 rides on the roller 16, and is wiped between the rollers 17 and 18 which may be adjusted in tension against each other. After 15 emerging between the rollers 17 and 18, the strip passes over the roller 19 and descends downward into the washing tank indicated more clearly in Figure 2. The mechanism in Figure 1 is described and operated as follows.
- 20 The rollers 12, 13, 14, and 15 are provided with split shafts, one end of which is mounted in the bearings 20, 21, 22 and 23 in the side plate 24, while the other end may be similarly mounted in the plate 25. As indicated in Figure 1, the rollers 12 and 14 at the right end pass through a plate 26 to the right of which is a collar 27 upon which the rolls 28 and 29 are mounted, while the shafts 12 and 14 are free to turn in the plate 26. The plate 26 is locked to these shafts for longitudinal motion, on the right by the collar 27 and on the left by a similar collar which is shown at the other side of the figure by the number 30. The pulleys 28 and 29 are operated through the belt 31 which is connected to a suitable motor 35 drive. The plate 26 is pinned by a pivot 32 to the link 33 which is pivoted at its other end to one end of a bell-crank lever 34 as shown at 35. The bell-crank lever 34 is pivoted by means of the pivot 36 to the block 37 mounted on the frame 7.
- 40 The other end of the bell-crank lever is attached by means of the forked pivot 38 to the crank arm 39 by means of the joint 40, which at its lower end is slotted to receive the flange 41 of the crank 39 and through which the pivot 42 passes.
- 45 The crank 39 is driven by the eccentric 43 which may be operated through a suitable motor from the shaft 44. A similar arrangement is provided for the shafts 13 and 15 and the two groups may be so geared up that they work in opposite directions. This may be easily done by driving the two bell-crank levers 34 and 49 from the crank arms at opposite ends of the shaft 44, these crank arms being set 180° out of phase to produce motion simultaneously in opposite directions.
- 55 In the operation of the system, the strip 1 picks up a certain amount of abrasive from the bath 5. This abrasive may comprise fused aluminum oxide, commonly known as "Alundum" in a mixture of ethylene glycol with a small amount of gum arabic to increase the jell of the mixture so as to provide a firmer resistance for working upon the strip. While the strip 1 may be rotated quite rapidly, the rolls 12 and 14 and 13 and 15, move very rapidly longitudinally back and forth. The rolls themselves may be made of "Alundum" grindstone or "Carborundum," or some other very hard abrasive surface. The abrasive mixture picked up by the 70 path is retained and acted upon by the rolls themselves so that an intimate rubbing is obtained against the strip without a very great pressure being applied. In addition to this, the abrasive action is uniform over the whole surface so that the surface cannot tear. The rolls

17 and 18 which act principally as wiping rolls are held against one another by means of the bearing supports 45 and 46 which may be tensioned to each other by means of the wing nuts 47 and 48 for suitable and desired tension. After the strip has passed over the abrasive end of the device, it comes down into a washing tank 50 which is provided with a roll 51 similar to the roll 6. The tank 50 is supported by ears 52, 53, by means of the shaft 53 mounted on the angles 54 of the frame 55.

After the strip 1 has come out of the tank it is further sprayed by means of the spraying pipes 56, 56, connected to the box 57 which is fed by means of the hose 58. From the spray tank, the strip passes over the wringing rollers 59, 60, 61 and 62, the latter of which may be so adjusted to wring the strip 1 fairly dry, although this process is fully completed in the arrangement to follow. From the wringing rollers the strip passes over the two driving rollers 63 and 64 in the manner shown. These two rollers 63 and 64 are mounted on the shafts 65 and 66 respectively, which are supported in the bearings 67 and 68, and are driven in geared relation by means of the gears 69 and 70 from the pulley 71 through the driving system comprising the shaft 72, the pulley 73 and the belt 74. The rollers 63 and 64 furnish the drive over the entire system, drawing the foil over the entire abrasive end of the machine and preparing the foil for the final winding up process.

While the drive may be entirely set at the points indicated in Figure 2, nevertheless, it is also possible to supplement this drive by a drive at a previous point in the system when the two points are properly adjusted with respect to each other, so that the speed will be maintained standard. The foil after passing between the rollers 63 and 64 and coming up from the bottom of the lower roller, ascends vertically to the top roll 75 positioned across the top beam 76. In the frame beneath the strip 1, is positioned a heating lamp 77 which sends its heat upward in the general direction of the strip, and dries it as it moves over the top of the frame. The strip 1 descending in back of the frame, is controlled by means of the guide 78 which is shown in detail in Figure 3. This guide 78 is pivoted to the shaft 79 in the support 80 of the frame and tends to preserve the alignment of the strip as it is being finally wound up in a roll as indicated at 81 in the back of the frame. The roll 81 is wound on a spindle 82 and tensioned by means of a spring tension which is shown more in detail in Figures 7 and 8. This tension is maintained in such a way that the roll slips sufficiently to wind just enough to keep a uniform tension on the strip as it emerges from the driving rolls 63 and 64. This is shown in detail in Figures 7 and 8.

Upon the cross beam 83 Figure 2 is mounted a bracket or support 84 which carries the mechanism for rewinding the foil after the treatment has been completed. A fitting 85, Figure 8, having a long barrel and a flange element is provided with the flange extending outwardly from the barrel and bolted to the support by bolts 86. The barrel fits in the support 84 and is open at the inner face to receive the sleeve or rod 87 which is adjustable in position in the barrel by means of the thumb screw 85' threading through the end of the barrel 85 and into the sleeve 87 for the purpose presently to be explained. A shoulder end collar 88 is provided

at the end of the rod 87 and this collar extends in the shaft 91. Two ball bearing fittings 89 and 92 are provided about the collar 88 and the shaft 91 respectively supporting the spindle 90 in the shoulders 88' and 93 and the spindle is held to the shaft by these fittings and the nut 94 threaded to the end of the shaft 91.

The spindle 90 is provided with a flange 106 bearing against the face of the pulley 100, which in turn is pulled against the ball bearing fitting 103. This bears against the spring washer 105 which is positioned between the bearing 103 and the washer 104 resting against the end of the barrel 85. It will readily be seen that by screwing up the thumb screw 85', the tension on the spring washer 105 will be increased and thus the friction of the flange 106 against the pulley face is similarly increased. This friction is increased to obtain sufficient tension between the pulley 20 and the spindle to approximately equal the tension on the spindle from the winding and allow sufficient slip in the system so that the foil is wound without exerting too great a strain on it.

In Figures 4 and 5 the means by which the abrasive rolls may be replaced is illustrated. As shown in Figure 4, the roll 12 is provided with a shoulder 107, and an end shaft 108 which is adapted to fit in the chuck collar 109. The shaft 108 is placed in the hole in the collar 109 and tightened by means of screwing down the collar 109 on the jaw elements 110, which may be made as illustrated in Figure 6 with three sectional jaws 111, 112 and 113, with a clearance 35 between each section as illustrated by 114 which is taken up when the collar 109 is tightened thus gripping the shaft 108 firmly in place. The other end of the chuck is formed with the shaft 115 passing through the plate 25 as shown in Figure 1. Both ends of the abrasive rolls 12, 13, 40 14 and 15 are made in the same way, so that they may be disassembled and new abrasive rolls substituted when the old ones become worn. The balancing mechanism for balancing and guiding the foil is illustrated in Figure 3. This comprises a frame 116 rectangular in shape, at the top of which is a cross guiding plate 117 having a guiding groove 118 formed by the outwardly extending pieces 119 and 120. At the lower end 50 of the frame there is provided an angle element 121 holding a roller 122.

The lower end of the frame has a centrally projecting V support 123 with an insulating strip 123' forming a part to insulate the top part of the frame from the base which is fastened to the external machinery. From the support 123 there extends at right angles a shaft 124, mounted to oscillate freely in the bearing 125 which is a part of the assembly including the collar 126 freely positioned but fixed by set screw 126' on the shaft 79. This latter adjustment allows the frame to be tilted in the proper desired direction to have the guide 115 properly work against the foil.

The frame is therefore quite free to oscillate in the plane of the frame which is at right-angles to the normal travel of the foil. If the foil tends to move one way or the other, the frame will follow it always guiding it however to the lower end which relatively on account of the point of pivot, holds its true position with reference to the roll 81. The roll 81 is slightly crowned so that the foil centers at the mid-point

of the roll. By arrangement the foil is wound in exactly the same manner as it was before being unwound and may be used on any type of winding machine in the same manner as it might have been used if it had not been unrolled in the first place. The roll when wound upon the spindle 90 may be removed and a new roll treated. It may be noted that since the driving end is quite near the rewinding spindle, very little foil will be wasted in the process, and since all of the foil has been treated before reaching the rolls 63 and 64, the complete roll will all have been treated when the end of the strip comes out of the driving rolls and the winding will automatically continue until the entire roll is wound up. The speed at which the roll may be treated, depends upon the nature of the treatment desired, the width of the roll, and the relative speeds of oscillation of the grinding of the rolls with reference to the driving speed of the foil over the 20 whole machine.

Initial tension may be placed upon the system by means of the weight 127 sustained as a brake upon the pulley 128 on the shaft 192 of the initial roll 2.

The foil treated in this manner described above as has been stated, is particularly useful in electrolytic condensers and has proved to be superior to the chemical treatment whereby only a heterogeneous roughing of the surface is obtained. In the present type of treated foil, not only is the roughing more uniform, but it is sharper and makes possible the attainment of a comparatively large surface area. As far as the method of treatment is concerned, this has been outlined above in the description of the apparatus and in the use of materials. The thickness of foil may on account of the treatment be materially increased showing that the peaks raised by the treatment are substantial as compared with the 40 original foil thickness.

While it has been specified that the liquid used is ethylene glycol and the abrasive material, fused aluminum oxide or "Alundum," it is possible to use other liquid carriers such as glycerin and certain oils, although ethylene glycol appears to stand up longer and allow more active use of the abrasive elements. Instead of "Alundum," "Carborundum" may be used or some material as for instance natural emery. The treatment consists primarily of carrying the liquid abrasive compound over abrasive rolls which move transverse in pairs to the direction of travel of the foil itself, the foil serving as a carrier for the liquid abrasive mixture which is worked against the 55 foil by means of the longitudinal motion of the rolls. It will also be noticed the rolls all turn in the the same direction, but since the foil is on opposite sides of successive rolls, the relative motion of the rolls and foils is such as to balance 60 or cancel any tendency for the grinding rolls to pull the foil through the grinding system.

Having now described my invention, I claim:
A method of preparing aluminum foil for electrolytic condensers which consists in passing the 65 foil through a viscous bath composed of ethylene glycol and an abrasive material mixed therewith allowing the foil to be drawn over a group of abrasive surfaces moving transversely to the foil each in opposite direction to the other whereby the abrasive compound provides the working 70 abrasive on the foil.

STRATFORD B. ALLEN.
